(57) **CLAIM**

The ornamental design of an electrical enclosure, as shown and described.

DESCRIPTION

FIG. 1 is a front, top and right side perspective view of an electrical enclosure showing my new design;

FIG. 2 is a top plan view thereof;

FIG. 3 is a bottom plan view thereof;

FIG. 4 is a right side elevation view thereof, on a larger scale;

FIG. 5 is a left side elevation view thereof;

FIG. 6 is a front elevation view thereof; and,

FIG. 7 is a back elevation view thereof.

The broken line portions of the figure drawings are included to show unclaimed subject matter only and form no part of the claimed design.

1 Claim, 4 Drawing Sheets
